UNITED STATES PATENT OFFICE

2,577,203

BAR FEED LOADER FOR METAL-
WORKING MACHINESEugene S. Mariotte, Syracuse, N. Y., assignor to
Lipe-Railway Corporation, Syracuse, N. Y., a
corporation of New York

Application April 26, 1946, Serial No. 665,279

1 Claim. (Cl. 29—60)

1

This invention relates to bar stock feeds for automatic metal working or screw machines, of the type of automatic bar feeds, in which the bars are fed in a cylinder or tube by means of a push plunger, through and beyond the rotating spindle of the metal working machine to a stop, where tools of the machine operate on the projecting end portion of the bar to form an article thereof which is automatically cut off when finished, and has for its object a feed cylinder in which the bars are fed sidewise through a lengthwise slot which is at least the length of the bar, which slot is normally closed by a closure, which is a segment of the wall of the cylinder.

The invention also has for its object the feeding of the bars one by one from a stack or a magazine into the cylinder through the side thereof in front of the push plunger therein. It further has for its object the controlling and timing of power mechanism for actuating the push plunger in a forward direction to feed the bar and in the reverse or retrograde direction to withdraw the plunger to starting position after the bar has been fed to the limit of its movement and has become too short for a finished article, and the feeding of a new bar into the cylinder in front of the retracted plunger, which controlling and timing is in turn controlled by the position of the push plunger, when it reaches the limit of its movement in a forward or feeding direction, and also when it reaches the limit of its movement in a retrograde or withdrawing direction.

The invention consists in the novel features and in the combinations and constructions hereinafter set forth and claimed.

In describing this invention, reference is had to the accompanying drawings, in which like characters designate corresponding parts in all the views.

Figure 1 is a side elevation, partly broken away, of a bar stock feed embodying this invention.

Figure 2 is an enlarged vertical sectional view taken approximately on the plane of line 2—2, Figure 1.

Figure 3 is an elevation, partly in section, of the control and timing mechanism.

Figure 4 is a sectional view taken on the plane of line 4—4, Figure 3, with the control box partly in elevation and partly broken away.

Figure 5 is a diagrammatic and schematic view of the control system.

This bar stock feed includes, generally, a feed cylinder or tube for receiving the bar and formed with a lengthwise segment in one side thereof having an opening and closing movement, the

segment being of at least the length of one of the bars to be fed, a push plunger or piston movable in the cylinder in one direction to feed the bar to the metal working machine and in the reverse direction to starting position, when the bar is used up to a remnant too short to form an article or to bridge the space between the end of the spindle of the metal working machine and the stop, power means for actuating the plunger or piston in reverse direction, and mechanism controlled by the plunger when at the limit of its feeding movement for controlling the power mechanism to withdraw the plunger to starting position and controlled by the plunger, when in starting position, to open the segment of the cylinder, the feeding of the new bar in the cylinder in front of the plunger, the closing of the segment and the operation of the power means to actuate the plunger to feed the new bar.

20 1 designates the cylinder or tube, which is suitably supported by frame members or pedestals 2 with the front end at 3 thereof either extending into the spindle of the machine tool or terminating but a short distance from the outer end of the spindle, so that the bar may bridge the gap when being fed, as is well understood. Reference may, however, be made to my Patents Nos. 2,327,916, issued August 24, 1943, and 2,300,457, issued November 3, 1942.

25 4 designates the segment in one side of the tube, which has an opening and closing movement.

30 As here shown, the cylinder is mounted in the angle of brackets 5 spaced apart at intervals along a rock shaft 6 supported by the pedestals 2, as by brackets 7. The segment 4 is carried by yokes 8 pivoted at 9 to the ends of the rock arms 10 and having hubs 11 mounted on the shaft 6 to rock therewith. The yokes 8 are adjusted in a predetermined radial position relative to the pivots 9 and held in said position in any suitable manner, as by set screws 12. The ends of the yokes at 13 form part of the cut-off and escape- 35 ment mechanism for the bars from the magazine, as will be presently described.

40 45 The magazine merely consists of a track 14 inclined slightly out of the vertical and supported by the brackets 7, and also guide strips 15 opposed to the track at intervals along the same and supported by brackets 16 rising from one of the angular walls of the brackets 5. The bars, designated B, are normally stacked in the space between the track 14 and guide strips 15 and are controlled in their feeding out of the magazine by a cut-off slide 17 controlled by the 50 55 rocking of the shaft 6, and hence by the open-

ing and closing of the segment or closure 4 or the yokes 8. When the segment or closure 4 is closed, the lowermost bar in the magazine rests on the surfaces 13 and the cut-off slide 17 is retracted from its position shown in Figure 2 against the action of a spring 18 by a shift arm or fork 19 projecting from the hub 11. When the segment 4 opens, the bar resting on the escapement surfaces 13 therein drops into the cylinder 1. During this movement, the spring 18 presses the slide 17 into cut-off position, as seen in Figure 2. As the segment closes by the rocking of the shaft 6 through the rock arm 10 and yoke 8, the surface 13 thereof moves into position to receive the next bar B, as the cut-off slide 17 retracts from its position shown in Figure 2 against the action of the spring 18 under the action of the fork 19. There are a plurality of yokes 8 and rock arms 10 on hubs 11 spaced apart along the shaft 6. Also, there is one cut-off slide similarly spaced for each yoke 8.

The rock shaft 6 is actuated by power means including a motor, and as the power used is compressed air, the motor is here shown as a double acting cylinder and piston motor. 20 is a cylinder and 21 the piston rod which is connected at 22 to a rock arm 23 on the hub 11. There are preferably two of these cylinder and piston motors, as seen in Figure 1, carried by the pedestals 2 for rocking the shaft 6. The hubs 11 at the ends of the shaft 6 of the mechanism for opening and closing the segment 4 only are provided with rock arms 23, to which piston rods 21 are connected, as there are but two motors.

25 designates the push plunger movable in the cylinder 1. The power for actuating this in the forward feeding direction is air, and for withdrawing it to starting position is vacuum. Hence, the control mechanism includes valve means for controlling the air and the vacuum. One of the features of this invention is that the control valve means is operated by power mechanism including motors, which in turn are controlled by the position occupied by the piston or plunger 25, when at the limit of its feeding movement, as shown in broken lines in Figure 5, and at the end of its withdrawing movement, as shown in full lines in Figure 5. The control mechanism is located in a box 26. It is shown as including a valve member 27, as a conical valve head rotatable in a suitable casing 28 supported by the wall 29 of the box 26. It is operated or indexed to its various positions by a plurality of air motors 31, 32, 33 and 34 of the cylinder and piston type. The cylinders have, respectively, ports 36, 37, 38 and 39, which are combined inlet and exhaust ports. The pistons 41, 42, 43 and 44 are connected by rods 45, 46, 47 and 48 to operate pawls 49, 50, 51 and 52 co-acting with the ratchet wheel 53 on a shaft 54 mounted in a suitable bearing 55 in the wall 29 of the control box and coupled to the valve member 22. The valve member 27 is pressed in the conical bore of the conical casing 28 by a spring 56. The pistons 41, 42, 43 and 44 in the cylinders 31, 32, 33 and 34 are single acting and are returned after air is released in the cylinders by springs 82, 83, 84 and 85. Each of the pawls 49, 50, 51 and 52 is here shown as provided with a discoidal hub 86 mounted on a pivot 87 on the end of one of four arms 88, 89, 90 and 91, which are pivoted to rock about a pivot 92 common to all of them, the piston rods 45, 46, 47 and 48, each being secured to one of the arms 88, 89, 90 and 91. Each of the pawls is biased toward en-

gaging position by torsion springs 93, 94, 95 and 96, respectively, coiled around the piston rods and each anchored at one end to one of the piston rods and the other anchored to the hub 86 of its companion pawl. The cylinders 31, 32, 33 and 34 are mounted to oscillate about pivots 97, 98, 99 and 100 during the movement of the piston, in order to conform to the movements of the pawl carrying arms 88, 89, 90 and 91.

The operation of the timing and indexing mechanism is as follows, referring to Figure 5. As the stock is exhausted, the plunger 25 in the feed tube or cylinder 1 is in the dotted line position, Figure 5, and uncovers the port 57. The low-pressure air then feeds through the pipe line 58 to the motor 32 to index the control valve 27 to first position where a vacuum line is connected to the rear or left end of the feed tube 1 by way of pipe 80, valve passage 75, and line 71. As the plunger 25 is withdrawn by the vacuum to the full line position Figure 5, it shifts the relay valve 69 to admit the high pressure to the indexing cylinder 31 to shift the control or indexing valve 27 to the second position where high pressure is admitted to the lower end of the cylinders 29 below the pistons therein by way of high pressure line 59, valve passage 63, and lines 64, 65. The air above the pistons in the cylinders 20 at this time exhausts through line 66 and valve passage 67. This operation of the pistons in the cylinders 20 opens the closure 4 of the feed tube 1 to admit a new stock bar from the magazine. As the closure 4 is thus opened, the relay valve 60 is actuated to admit high pressure to the indexing motor 33 by way of line 59, relay valve 60 and line 61. This indexes the control valve 27 to the third position where the high pressure enters the upper ends of the cylinders 20 by way of high pressure line 59, valve passage 63, and line 71 to close the closure 4 of the feed tube 1. The air exhausts from the lower ends of the cylinders 20 through lines 72, 73, and passage 67 of the control valve 27. As the closure of the feed tube 1 thus closes, the relay valve 60 is activated and shifted to admit the high pressure to the cylinder 34 of the indexing motor by way of lines 59, relay valve 60 and line 74. This operation indexes the control valve 27 to fourth position where low pressure is admitted to feed tube 1 in the rear of the feed plunger 25 by way of line 76, control valve passage 75 and line 71. As the feed plunger is again moved forward and the stock bar again exhausted, the cycle repeats.

The reversing valve 60 comprises a casing and a shiftable member 61A therein, which casing is connected to either the line 61 to the motor 33, or the line 74 to the motor 34 by the opening and closing of the closure 4 of the feed tube 1. The valve 69 constitutes a relay device common to the high pressure branches 59, 68, and low pressure branch 77. The valve 60 constitutes a reversing relay device in the high pressure branch 59, 61, 74. The port 57 is a relay device in the branch 58.

The control member or valve 27 is controlled or indexed in its operation by the position of the push plunger 25 at the end of its feeding movement and at the start of its feeding movement. The opening and closing of the segment closure 4 of the magazine is controlled also by the plunger 25, when it is at or approaches its retracted position, and the motor or motors 20, which open and close the segment 4, are double acting and the closure 4 is held air tight closed

all during the feeding operation by air pressure in the motors. The reversing valve member 61A for the motors 20 is operated by the opening and closing movement of the segment 4, as the high pressure air goes directly to these motors or does not pass through the indexing valve.

What I claim is:

A bar stock feed for metal working machines including a feed tube for the bar, the tube being of such length as to enclose a bar, the tube comprising a body section having a lengthwise slot long enough to receive the bar to be machined, through which slot the bars are placed sidewise into the body section, and a closure section, one of said sections being shiftable relatively to the other to open and close the slot, a reversible power motor to operate the shiftable section, a feed plunger reciprocally movable in the tube, and a control mechanism for said feed plunger and reversible power motor, said control mechanism including means for selectively supplying power to said feed plunger to advance and retract the same and means for selectively sup-

plying power to said reversible motor to open and close said shiftable section, power operated indexible means for selectively actuating said power supplying means, and a plurality of relay means actuated by said feed plunger in its extreme positions and by the shiftable section in its extreme position for selectively supplying power to said indexible means.

EUGENE S. MARIOTTE.
